UNITED STATES PATENT OFFICE.

JAFEW S. VAN BUREN, OF ALBANY, NEW YORK, ASSIGNOR TO RATHBONE, SARD & CO., OF SAME PLACE.

DESIGN FOR A COOKING-STOVE.

SPECIFICATION forming part of Design No. 16,801, dated July 13, 1886.

Application filed April 22, 1886. Serial No. 199,854. Term of patent 3½ years.

To all whom it may concern:

Be it known that I, JAFEW S. VAN BUREN, of Albany, in the county of Albany and State of New York, have invented certain new and useful Improvements in Design for Stoves; and I do hereby declare the following to be a full, clear, and exact description of the invention, such as will enable others skilled in the art to which it pertains to make and use it, reference being had to the accompanying drawing, which forms part of this specification.

My invention relates to designs for cooking-stoves; and it consists in the ornamentation which will be more fully described hereinafter, whereby a new and pleasing effect is produced.

The accompanying illustration represents a cooking-stove embodying my design.

The base A of the stove is ornamented by the conventional representation of sprigs containing leaves and flowers, and the four legs B, of grotesque design, and four outward and downward curved flowery ornamented strips, C.

The oven-door D has a name-plate or center ornament, E. Around this is a wreath of leaves arranged inside of a ring, F. Upon the door, outside of the ring F, are sprigs containing leaves and flowers of conventional form.

Upon the reservoir and closet panel H, extending from the top to the bottom of the stove, are formed two designs, which, though separated by the line I formed by the door J, really form a continuation of a single design.

Upon the upper portion of the panel H is 35 formed a conventional representation of a sprig and flowers, and upon the door J is formed a volute ornament, L, as shown.

Upon the fire-door N is a central flower, which is partially surrounded by sprigs, leaves, 40 and flowers, as shown.

Having thus described my invention, I claim—

1. A design for a stove, formed by the feet B, ornamented with a grotesque face and the 45 outward and downward curved flowery ornamented strip C, as shown and described.

2. In a design for stoves, the base of the same, having the sprigs, flowers, and leaves, as shown and described. 50

3. In a design for a stove, the oven-door, consisting of the central face, E, the surrounding ring F, and the branches, flowers, and leaves which extend partially around the ring, substantially as shown. 55

4. In a design for a stove, the panel H, consisting of the volute L, as shown.

5. In a design for a stove, the fire-door N, consisting of a large central volute partially surrounded by two branches upon which are 60 leaves and flowers, as shown.

In testimony whereof I affix my signature in presence of two witnesses.

JAFEW S. VAN BUREN.
